UNITED STATES PATENT OFFICE.

HIRAM STEVENS MAXIM, OF LONDON, ENGLAND.

AUTOMATIC MACHINE-GUN.

SPECIFICATION forming part of Letters Patent No. 447,837, dated March 10, 1891.

Original application filed December 28, 1886. Serial No. 222,849. Divided and this application filed October 18, 1889. Serial No. 327,459. (No model.) Patented in France June 19, 1886, No. 169,647, and February 12, 1887, No. 181,516; in England June 1, 1886, No. 7,354; in Germany January 20, 1887, No. 41,870; in Belgium September 26, 1887, No. 79,005; in Italy November 26, 1887, No. 22,500, and in Austria-Hungary April 21, 1888, No. 34,166.

To all whom it may concern:

Be it known that I, HIRAM STEVENS MAXIM, mechanical engineer, a citizen of the United States, and a resident of London, England, have invented certain new and useful Improvements in Automatic Machine-Guns, (for which I have obtained patents in the following countries: in Great Britain, No. 7,354, dated June 1, 1886; in France, No. 169,647, dated June 19, 1885, certificate of addition to No. 169,647, dated October 15, 1886, and No. 181,516, dated February 12, 1887; in Belgium, No. 79,005, dated September 26, 1887; in Germany, No. 41,870, dated January 20, 1887; in Italy, No. 22,500, dated November 26, 1887, and in Austria-Hungary, No. 34,166, dated April 21, 1888,) of which the following is a specification, reference being had to the accompanying drawings.

This application is a division of an application filed by me December 28, 1886, Serial No. 222,849.

The invention subject of my present application involves the application to the heavier types of guns of an automatic means for operating the same.

The general character of the gun to which the present invention relates is as follows: The barrel and breech-block are both capable of a certain range of longitudinal movement which takes place after a discharge as the effect of the recoil normally, and during the first part of the backward movement of these two parts they are securely locked together, the breech-block in position to close the breech. Having reached a certain point in their recoil, the interposition of any suitable device unlocks or releases them from engagement, whereupon the barrel returns to its normal or forward position, while the breech-block is locked or restrained against forward movement or by its momentum continues for a short distance its recoil and is then locked. Some device capable of storing the energy of the recoil of these parts is utilized to return the barrel to its position, and another and similar device, such as a spring, is similarly employed in connection with the breech-block, which is released and permitted

to move forward when the barrel has reached its forward position, or nearly so. These movements or changes of position of the parts I have utilized in effecting automatically the operations of loading and firing the gun—that is to say, the recoil of the barrel withdraws a cartridge from a suitable feed mechanism and leaves it in position to be subsequently dropped or forced into line with the breech-block and breech. The separation of the breech-block and barrel extracts the empty shell from the latter and permits the loaded shell to move into line with the barrel. The forward movement of the breech-block drives the shell home and trips the hammer previously cocked by some one of the moving parts.

This apparatus or combination of devices I have found desirable to be modified when used with large guns in substantially the manner illustrated in the drawings, and hereinafter described in detail.

Figure 1 is a plan, partly in horizontal section, of one form of my improved gun. Fig. 2 is a vertical longitudinal section of the same, partly through the center of the gun and partly through one of the buffers hereinafter described. Fig. 3 is a vertical longitudinal central section showing the parts in a different position. Fig. 4 is a transverse section on the line xx' , Fig. 1. Fig. 4^a is a horizontal section of part of the gun on the line $x'x'$, Fig. 2, drawn to an enlarged scale. Figs. 5 and 6 are plans, and Fig. 7 is a vertical longitudinal central section, drawn to the same scale as Fig. 4, showing details of construction. Fig. 8 is a horizontal section on the line yy' , Fig. 4, showing means for locking the breech-block to the barrel. Fig. 9 is a vertical longitudinal central section illustrating the means for holding back and releasing the breech-block of the said gun, as hereinafter described. Fig. 10 is a rear elevation of the said breech-block. Fig. 11 is a front elevation of a portion of the same. Fig. 12 is a side elevation, partly in vertical longitudinal central section, showing one of my guns supported upon a cylindrical mounting. Fig. 13 is a plan of the said mounting, partly in hori-

zontal section. Fig. 14 is a section of the line $y' y'$, Fig. 12.

In guns of this kind it will be understood that the cartridges or shells are very long, as a heavy charge of powder is required. I therefore make the breech-block very short, preferably of a length equal to two calibers, in order to economize space and to lighten the gun.

10 A is a strong metal frame or cradle, which is supported by means of its trunnions A' on a suitable carriage or mounting.

15 B is the barrel, which is fitted to slide longitudinally to and fro in the said frame or cradle.

15 C is the breech-block, which is fitted to slide longitudinally in guides A'' in the frame or cradle A to and from the barrel B. The barrel is constructed with a forked rearward extension B'. The breech-block C is T-shaped in transverse section, and its upper or wider part engages with and slides in the guide-grooves A'', while its lower or narrower part fits into the forked extension B' of the barrel when the breech is closed. The barrel is connected at its rear end with hydraulic buffers P for counteracting its recoil. The ram or piston of each of these buffers is acted upon by a spring E for storing energy during the recoil and utilizing such energy to effect the return movement of the barrel.

30 The breech-block has firmly connected therewith at its upper end a frame Q, which is fitted to slide to and fro with the breech-block in the guides A'', and which is formed with an aperture Q' for the reception of a cartridge, which, when the breech is closed, rests upon the upper edges of the guides A''.

35 The magazine consists of a vertical hopper or feeder K, beneath which slides the frame Q, so that when the breech is closed the lowermost cartridge in the magazine will drop into the frame Q, as shown in Fig. 2. In the recoil or backward movement of the breech-block C and frame Q this cartridge will be drawn back until it reaches such a position that it can pass between the edges of the guides A''. It will then fall into the position shown in Fig. 3, so that it will be thrust into 45 the barrel by the breech-block in the next forward or return movement thereof. The hopper or magazine K is constructed with an internal projection K', upon which the forward end of a cartridge will rest until the rear end of the cartridge is allowed to fall, when the said cartridge will be moved a short distance backward by the inclined surface of the guide-groove K'' for the flanges of the cartridges, thus disengaging the forward end 55 of the said cartridge from the said projection K' and allowing the cartridge to fall into the frame Q.

60 Two springs D are provided for storing energy during the backward movement of the breech-block and for utilizing such energy to effect the return movement of the said block. These springs are inclosed within the sides

of the frame Q and are attached at their forward end to the gun-frame A and at their rear end to the breech-block.

70 For locking the breech-block to the barrel, I provide two bolts, rods, or shafts R R', which are fitted in the breech-block, so that they can be rotated or partially rotated about their axes. These bolts or shafts are semi-cylindrical throughout a portion of their length, and their semi-cylindrical portions are adapted to enter notches in the extension B' of the barrel, as shown in Fig. 8, for the purpose of locking the breech-block to the barrel 75 and efficiently supporting the said block against the force of the explosion, so that the breech-block and barrel will recoil together. The turning of the said bolts or shafts R R' about their axes through a small angle will 80 unlock the breech-block from the barrel by bringing the flat sides of the semi-cylindrical portions of the bolts flush with the sides of the breech-block. The said block is then free to move backward away from the barrel. On 85 the bolts or shafts R R' are fixed pinions R'', which are geared with each other and with racks S'' on a slide S, arranged above the breech-block between the guides A'' and provided with a handle S', whereby it may be 90 drawn back to effect the opening of the breech by hand. The slide S is connected with the breech-block by a bolt T, which is free to slide to and fro in the said block through a distance equal to that through 95 which the slide S has to move to effect the unlocking of the breech-block. Therefore by pulling the handle S' backward the breech-block will first be unlocked from the barrel and then drawn back to open the breech.

100 To provide for the automatic opening of the breech, an arm F, having an inclined surface F', is fixed upon the lower end of the bolt or shaft R, and is so arranged that in the recoil it will strike an inclined shoulder or projection F'' on the gun-frame A. The bolts R R' will thus be partially rotated about their axes, so as to unlock the breech-block from the barrel. Another arm G is fixed upon the bolt R, and a spring G' is firmly attached 105 to the gun-frame A in such a position that when the breech-block is driven home the arm G will strike and compress the spring G', which by its reaction upon the said arm will turn the bolts R R' into their locking position.

110 The hammer H' is pivoted upon a vertical axis and is acted upon by a spiral spring H'', surrounding its pivot J.

115 The sear I is arranged to be acted upon by an arm or lever G'', fixed on the bolt or shaft R', so that when the said bolt or shaft is turned to lock the breech-block to the barrel the said sear will be automatically disengaged from the bent of the hammer, which is formed in a disk J', fixed on the pivot J.

120 The sear I' is arranged in combination with a trigger M and sliding bar M', whereby it may be disengaged from the hammer by hand to fire the gun. The breech-block re-

coils with the barrel, and is then unlocked therefrom and continues to move backward by reason of its momentum.

Any suitable means are provided, if necessary, for retaining the breech-block in its rearmost position while a cartridge falls in front thereof and then releasing the said block to permit its forward movement. I sometimes employ for this purpose the devices shown in Figs. 9, 10, and 11—that is to say, a bar or catch C' is pivoted to the breech-block and is formed with a hook C''. This bar or catch is acted upon by a spring I, which tends to push it downward. At the termination of the backward movement of the breech-block the hooked end of this bar passes through an aperture in the rear end of the frame A and engages with the said frame, thus holding back the breech-block until released, as hereinafter described. A bar T' is fitted to slide to and fro in a transverse slot in a pin or shaft T'', whereby the said bar is pivoted to the breech-block, so that it works in a hole or slot therein. A pin V is passed through the said bar to prevent its withdrawal from the breech-block, and a spring V' is firmly secured to the said bar and presses against the lower wall of the slot in the breech-block, so that it tends to push the said bar against the upper wall of the said slot. A sliding bar V'' is secured to the frame A and serves as a connection between the bars C' and T'. In its rearward movement of the breech-block the rear end of the bar T' strikes the frame A, and is thus pushed forward into the position shown in Fig. 9 at the same time that the hook C'' engages with the said frame. When the cartridge which has been drawn back by the breech-block falls in front of the said block, its head or base strikes the bar T', thereby turning the same on its pivot, so that it pushes the sliding bar V'' upward against the bar C''. The hook C'' is thus disengaged from the frame A and the breech-block released and permitted to move forward.

An extractor N is fitted to slide in a hole or cavity in the breech-block C, and is formed with an elongated slot N', through which is passed a pin N'' for retaining the extractor in the breech-block while permitting the said block to move backward through a short distance before it operates the extractor to extract the empty cartridge-shell from the barrel.

O is the firing-pin, which is of the usual construction.

To provide for supporting the forward ends of the cartridges when they fall into the loading position, I employ a bent bar U, which is fitted to slide in suitable guides beneath the barrel. The rear end of this bar extends upward and forms part of the seating for a cartridge in the barrel. A spiral spring U' is placed upon the said rod and bears at one end against a lug N³ on the frame A and at its other end against a shoulder U'' on the

bar U. When the breech-block is unlocked from the barrel and moves away therefrom, the spring U' forces the bar U backward, so 70 that the cartridge drawn out of the magazine by the frame Q will fall upon the rear end of the said bar. The breech-block in its forward movement pushes the flange of the cartridge against the bar U, and thus compresses the 75 spring U' and moves the said bar forward until it comes against the breech end of the barrel. This gun can be advantageously worked by hand if the means for automatically unlocking the breech are dispensed with. 80

The operation of my improved gun is as follows, viz: To load the gun at starting, any desired number of cartridges are introduced into the hopper or magazine K and the lowermost of the said cartridges drops into the 85 frame Q. The handle S' is then pulled backward to unlock the breech-block and draw the same back in the frame or cradle A until the catch C'' engages with the rear end of the said frame or cradle, and thus holds back the said block. The cartridge drawn back by the frame Q then falls into the space between the breech-block and the rear end of the barrel, and striking the bar T' disengages the catch C'', and thus permits the return movement of 90 the breech-block under the action of the spring D. The cocking of the hammer H' is effected by the breech-block in its backward movement. In the forward or return movement of the breech-block the arm G strikes the spring G', and the bolts R R' are thereby turned so as to lock the said block to the barrel. The arm G'' at the same time disengages the sear I from the bent of the hammer. At the termination of the return 100 movement of the breech-block another cartridge falls from the magazine into the frame Q. The gun is now ready for firing, and it is fired by pulling the trigger M, and thus disengaging the sear I' from the bent of the 105 hammer. The force of the explosion causes the recoil of the barrel and breech-block in the frame or cradle A. In this recoil the springs E are compressed and the arm F, coming in contact with the inclined projection F'', turns the bolts R R' about their axes, thus unlocking the breech-block and allowing the same to continue its backward movement, while the barrel is moved forward or run out to the firing position by the reaction of the 110 spring E. The breech-block in its continued backward movement cocks the hammer, extracts the empty cartridge-shell, and through the medium of the frame Q draws a fresh cartridge out of the magazine. At the termination of the rearward movement of the breech-block the catch C'' holds back the said block until the said cartridge falls in front thereof. The said cartridge strikes the bar T', and thus disengages the said catch, 120 and the springs D, which have been compressed in the backward movement of the breech-block, react and effect the return movement of the said block. In the forward 125 movement of the breech-block the catch C'' holds back the said block until the said cartridge falls in front thereof. The said cartridge strikes the bar T', and thus disengages the said catch, 130 and the springs D, which have been compressed in the backward movement of the breech-block, react and effect the return movement of the said block. In the forward

or return movement of the breech-block the said cartridge is thrust into the barrel and the frame Q moved forward to receive a fresh cartridge from the magazine. The spring G', 5 acting upon the arm G, locks the breech-block to the barrel and the sear I is disengaged from the hammer by the arm G''. It will therefore be seen that all the operations, except the firing of the gun, are performed automatically. By fastening or holding back the trigger M the gun may, if desired, be rendered entirely automatic, so that it will continue firing successive shots so long as the supply of ammunition lasts.

15 According to another part of my invention I provide means whereby the gun when not in use for firing will be held in any position to which it may be adjusted, so that the turning of the same upon its trunnions will be 20 preserved irrespectively of the position for the time being of its center of gravity. For this purpose I combine with the shoulder-piece or crutch, means whereby when no pressure is exerted upon the said shoulder-piece 25 or crutch the gun will be firmly locked or secured against vertical movement; but when pressure is applied to the said shoulder-piece or crutch the gun will be free to be elevated or depressed, as required.

30 In Fig. 12 c is a tube or hollow rod secured in any convenient manner to the left-hand side of the frame A. For example, the said tube is passed through a ring or annular piece c', fixed on the said frame, and its end is inserted in a socket c'' also fixed on the said frame. A block d is secured in the forward end of this tube, and a spring-catch e is pivoted to the said block and is adapted to enter a hole in the socket c'' and engage with 40 the end of the said socket, as shown. A rod f is arranged within this tube and is formed with a head f' at its forward end, which is fitted to slide in the said tube. A curved arm g is pivoted at g' to the gun-mounting and is 45 passed through a hole or slot in the tube c. The said tube has a hollow block h, firmly attached to its rear end, and upon this block the shoulder-piece or crutch i is fitted to slide toward and away from the gun. Two levers j are pivoted to the block h within the 50 same. The short arms of these levers engage with shoulders on the rear end of the rod f. The long arms of the said levers are acted upon by springs k, which are secured to the block h, and which tend to push the crutch i outward upon the said block and to push the rod f inward, so that the arm g is tightly held between the head f' and the block d, and the swinging of the gun upon its trunnions is 55 prevented. When the gunner applies pressure to the said crutch with his shoulder, it is moved inward or toward the gun, the springs k are compressed, and the levers j are turned on their pivots. The rod f is thus drawn outward and the arm g released.

What I claim is—

1. The combination of the outer frame, the sliding barrel provided with a forked extension, one or more springs connected with the barrel for effecting its return movement after a recoil, the longitudinally-movable breech-block, one or more springs acting thereon to effect its return or forward movement after recoil, a locking device normally securing the breech-block to the barrel, a detent or device for releasing the same at the termination of the recoil of the barrel, whereby the breech-block is free to continue its backward movement, and means for relocking the barrel and breech-block together when in their forward position, as set forth.

2. The combination of an outer frame, a sliding barrel provided at its breech end with an extension and arranged to recoil in said outer frame at each discharge, a breech-block fitted to slide to and fro in said frame in rear of the barrel, bolts or shafts in said block formed with parts adapted when the bolts or shafts are turned to engage with grooves or notches in said extension of the barrel, and means for turning said bolts or shafts to lock or unlock the breech-block from the barrel.

3. The combination, with the breech-block and the locking bolts or shafts R R' therein, of the pinions R'', connecting said bolts or shafts, the arms F G, extending from one of the bolts, and inclined surfaces or projections on the gun-frame in the path of the arms F G for operating said bolts or shafts in the to-and-fro movement of said breech-block, substantially as set forth.

4. The combination, with the breech-block, the locking bolts or shafts R R' therein, and the pinions R'', connecting the same, of the slide S, connected to said block and formed with a part S' to serve as a handle, and racks S'' on the slide S, gearing with the pinions R'', as set forth.

5. The combination, with a sliding breech-block, of a hammer mounted on a vertical pivot or shaft thereon, a cam J' with a bent II on the hammer-shaft, a sear I, engaging therewith, a spring actuating the sear, a locking-bolt in the breech-block adapted to be rotated by the to-and-fro movement of the same, and an arm G'' on said bolt adapted to engage with the sear, as herein set forth.

6. The combination, with a reciprocating breech-block, of a hammer H', its vertical shaft J, the disk or cam J', formed with the bent II and secured to the hammer-shaft, the sears II', engaging with the disk J', the divided spring J'', bearing on the sears, an arm G'', extending from a rotating bolt or shaft R' in the breech-block, the sliding bar M', engaging with the sear, and a trigger M for moving the same, as set forth.

7. The combination, with a barrel and cartridge hopper or feeder, of a breech-block fitted to slide to and fro in the frame of the gun in rear of the barrel, and a frame Q, formed with the aperture Q', connected with

the breech-block and extending over the barrel and beneath the hopper when the breech is closed, as set forth.

8. The combination, with a stationary frame 5 A and sliding barrel B, of the hydraulic buffers P between the barrel and the frame, for counteracting the recoil of said barrel, and the spring E intermediate to the barrel and frame, for effecting the forward or return movement of the barrel, as set forth.

9. The combination, with the barrel and the breech-block adapted to slide to and fro in rear of the same, of the bent bar U, sliding in guides or bearings attached to said barrel, 15 and the spring U' intermediate to the bar and a lug on the gun-frame and adapted to force the bar U back on the separation of the barrel and breech-block, as set forth.

10. The combination, with a gun-frame, a 20 barrel, and a breech-block adapted to slide to and fro on the frame in line with the barrel, of a hook on the breech-block for engaging with the frame and holding said block at the rear end of its stroke or movement and a releasing 25 device adapted to be struck by the cartridges when falling into line with the barrel, and thereby caused to release said block and permit its forward movement, as set forth.

11. The combination, with the outer frame 30 A, the barrel, and the breech-block C, adapted to slide to and fro in said frame in line with the barrel, of the spring-catch C' on the breech-block for engaging with said frame when the breech-block has reached its limit of back- 35 ward movement, a pivoted spring-actuated

lever in position to be struck by the cartridges falling into line with the opening in the breech, and a plate or slide between said lever and the catch C' for disengaging said catch when the lever is struck by a cartridge, as set forth. 40

12. The combination, with a gun mounted on trunnions, of a shoulder-piece or crutch, a curved serrated arm or toothed segment secured to the stationary mounting, and a spring-actuated detent device carried by the crutch 45 and adapted to engage with said segment and hold the gun in any position to which it may be turned on its trunnions.

13. The combination, with a gun mounted on trunnions, of a tube attached to the gun-frame, a hollow block formed or fixed on said tube, a shoulder-piece fitted to slide on said block toward and away from the gun, a pair of clamping-jaws, one of which is fixed in said tube and the other of which is movable therein, a curved arm attached to the gun-mounting and extending between said jaws, one or more springs for operating said movable jaw to clamp said arm, and means whereby said movable jaw may be withdrawn and said arm 60 released by pressure against said shoulder-piece, substantially as and for the purposes set forth.

In testimony whereof I have hereunto signed my name in the presence of two subscribing 65 witnesses.

HIRAM STEVENS MAXIM.
